UNITED STATES PATENT OFFICE.

HUGO H. PLAUT, OF NEW YORK, N. Y.

DESIGN FOR AN ARTIFICIAL FEATHER.

SPECIFICATION forming part of Design No. 19,317, dated September 17, 1889.

Application filed January 19, 1889. Serial No. 296,949. Term of patent 3½ years.

To all whom it may concern:

Be it known that I, HUGO H. PLAUT, a citizen of the United States, residing at New York, in the county of New York and State 5 of New York, have invented and produced a new and original Design for Artificial Feathers, of which the following is a specification, reference being had to the accompanying drawing, forming part thereof.

10 The figure of the drawing represents a plan view of my newly-designed feather.

The letter *a* indicates the central rib or stem of the feather, which spreads out at the upper end into an approximate oval representing the "eye" of the peacock's tail-feather.

15 *b b* are a series of disks or facets disposed along the length of the rib *a* and its oval eye. Within said oval, arranged in curved lines, are other disks or facets *c c*. Extending outward on each side of rib *a* (except for a small

portion of the lower end) are feather-like rays *d d*, which give to said rib a feathery appearance. The central part of the oval eye, between its various disks, is also provided with feathery rays *e*. 25

In the further ornamentation of my design I prefer to use contrasting colors, and when thus finished it presents an exceptionally neat and attractive appearance, so that I term it the "peacock-feather" design. 30

I claim—

The design for artificial feathers herein described and shown, the same consisting of the rib *a*, disks *b* and *c*, and feathery rays *d* and *e*, showing an approximate representation of 35 a peacock's eye.

HUGO H. PLAUT.
